UNITED STATES PATENT OFFICE.

KATHERINE T. BARAL, OF NEW YORK, N. Y.

HAIR-BRUSH.

1,383,511.

Specification of Letters Patent.

Patented July 5, 1921.

Application filed July 24, 1920. Serial No. 398,626.

To all whom it may concern:

Be it known that I, KATHERINE T. BARAL, a citizen of the United States, residing at New York, in the county of New York and 5 State of New York, have invented certain new and useful Improvements in Hair-Brushes, of which the following is a specification.

This invention relates to improvements in 10 hair brushes and has as its primary object to provide a brush which will be wholly sanitary in that it is so constructed that the bristle carrying body thereof may be removed or separated from the back of the 15 brush and sterilized or otherwise thoroughly cleansed, the brush differing in this respect from the ordinary brush in which the bristles are set into the back, and which cannot be subjected to sterilization or to treatment 20 with chemicals or otherwise for the purpose of cleaning it, especially where the back and handle are of wood, celluloid, or some other material which would be liable to be affected either by heat or by the action of 25 any chemical substances employed for the purpose stated.

Another object of the invention is to provide, in a brush having a head which is separable from the back, a novel sectional 30 construction of head such that when the head is removed from the back and the sections thereof are separated, access may be readily had to all portions of the tufts of bristles for the purpose of freeing them 35 from accumulations of foreign matter and otherwise thoroughly cleansing them.

With regard to the head construction, the invention contemplates forming the said head in sections having spaced members 40 which extend substantially in parallelism with relation to each other and which carry the tufts of bristles, these members interdigitating when the sections are assembled so as to provide a substantially solid head 45 or backing for the bristles and, on the other hand, when the sections are separated, presenting the bristles for cleaning in relatively widely spaced rows so that the cleansing of the bristles may be more readily and eff- 50 ectually accomplished.

In the accompanying drawings:

Figure 1 is a perspective view of the brush embodying the present invention, the bristle carrying head being illustrated as 55 being separated from the back of the brush;

Fig. 2 is a vertical longitudinal sectional

view through the brush with the parts thereof assembled;

Fig. 3 is a plan view of the bristle carrying head, the sections thereof being assembled and the bristle tufts being shown in section so as to more clearly illustrate the construction of the said head;

Fig. 4 is a view similar to Fig. 3 but illustrating the sections of the head separated;

Fig. 5 is a vertical transverse sectional view through the brush;

Fig. 6 is a detail vertical longitudinal sectional view through a portion of the brush illustrating the means provided for holding the bristle carrying head assembled with the back.

Generally speaking, the brush comprises a back which is indicated in general by the numeral 1 and which is provided with a 75 handle indicated in general by the numeral 2 and further comprises a bristle carrying head 3 and provided with tufts of bristles indicated by the numeral 4. The back 1 and handle 2 may be made of any desired 80 material and ornamented or embellished in any desired manner, and inasmuch as these parts of the brush will not be necessarily subjected to any injurious degree of heat or to the action of cleansing preparations 85 which may be employed in treating the bristles of the brush, these said parts may be made of celluloid, wood, metal, or any of the other materials usually employed for the purpose or even of materials which have 90 not yet heretofore been employed because of liability to deterioration or injury through the action of heat or chemicals. On the other hand the bristle carrying head 3 preferably has its sections made of metal or 95 some other material which will withstand a sterilizing degree of temperature and the action of cleansing compositions.

The bristle carrying head 3 comprises two sections which are nearly of counterpart 100 form and one of which is indicated by the numeral 5 and the other by the numeral 6. Each of these sections comprises a side portion 7 which may be of the arcuate form shown in the drawings or of any other arcuate or straight line shape in conformity with the shape of the brush back 1. In the case of the section 5, the side portion 7 thereof terminates in terminal bristle carrying portions 8 which form continuations of the 105 said side member, and the side members 7 of both sections 5 and 6 are provided with

preferably integral bristle carrying members 9 which in the present instance extend parallel to each other and which are spaced apart a distance substantially equal to their 5 width. To all intents and purposes the terminal portions 8 may be considered as end ones of the series of members 9 which project from the side portions 7 of the member 5 inasmuch as these portions 8 are parallel 10 to the side members 9 and also carry bristle tufts. The bristle tufts 4 are set into the members 8 and 9 in rows and are also preferably set into the side members 7 of the two sections of the head and while this arrangement is preferable, it will be understood 15 that another arrangement may be effected without departing from the invention. The members 9 of the two sections 5 and 6 are alternately arranged or spaced so that 20 when the sections are assembled, the members 9 thereof will become interdigitated thus forming a substantially solid head carrying the bristles. When the sections are assembled in the manner stated, the extremities 25 of the members 9 of each section will engage the inner edge of the side portions 7 of the other section, and in order that the two sections may be held against relative displacement, the said extremities of all of 30 the members 9 are preferably beveled as indicated by the numeral 10, and the side inner edges of the side members 7 are undercut or beveled, as at 11, at points between the inner ends of the respective members 9 so that 35 the beveled portions will interlock as clearly shown in Fig. 5 of the drawings with the result stated.

When the sections 5 and 6 of the bristle carrying head are assembled, the outer 40 edges of the side members and the outer edges of the terminal portions 8 will extend along an unbroken outline defining the marginal contour of the bristle carrying head. Thus with the sections assembled, the head 45 may be disposed to fit snugly within a recess 12 which is formed in the under side of the back 1 of the brush and which is of a corresponding contour, and this recess is formed in the forward portion of its wall with a socket 50 13 designed to receive the projecting stud 14 formed upon one of the terminal portions 8 of the section 5 of the bristle carrying head. The other terminal portion of this section 55 of the head is formed with a socket 15 into which is projected the engaging end 16 of a latch 17 which is slidably mounted in a bore 18 formed in the shank of the handle 2. A spring 19 is housed within an enlarged portion of this bore and bears at one end against 60 a head 20 formed upon the inner end of the latch 17 and at its other end bears against any suitable stop element 22 which projects into or across the bore. An actuating button or finger piece 23 is provided at the rear 65 end of the handle, and a connecting element

24 is connected in any suitable manner to the latch 17 and extends through the bore 18 and is connected to the said button or finger piece 23. Thus when the button or finger piece is grasped and pulled rearwardly, the 70 latch 17 will be retracted, and the bristle carrying head of the brush may be disposed within the recess 12 in the back 1, or it may be removed from this recess if already in place therein. On the other hand when the 75 finger piece 23 is released the spring 19 will project the latch so as to cause the engaging end thereof to seat in the socket 15 and this together with the engagement of the stud 14 in the socket 13 will serve to securely 80 hold the bristle carrying head connected with the back.

Returning again to a consideration of Fig. 4 of the drawings which illustrates the sections of the bristle carrying head relatively separated, it will be evident that inasmuch as the bristle carrying members 9 are relatively widely spaced, and the bristle tufts are carried upon these members in rows, the rows of bristles upon each section 90 of the head, when the sections are separated, will be likewise somewhat spaced so that as a result access may be more readily had to the bristles and they may be more thoroughly cleansed. Thus when the sections 95 comprising the bristle carrying head of the brush are relatively separated, their separation results, in effect, in a relatively wide spacing of the bristle tufts so that the cleaning of the bristles may be more readily effected.

Having thus described the invention, what is claimed as new is:

1. In combination, a brush back having a facial recess, a brush head removably seated in said recess and comprising sections having coöperating side members forming a marginal brush head rim, transversely extending spaced interfitting members carried by the side members, and bristle tufts on 110 said side and interfitting members.

2. In combination, a brush back having a facial recess, a brush head removably seated in said recess flush with the said back and comprising sections having coöperating side 115 members forming a marginal brush head rim, transversely extending spaced interlocking members carried by the side members, the ends of the transversely extending members of one section having holding engagement with the side member of the other when the sections are assembled to the brush back, and bristle tufts on said side and interlocking members.

3. In combination, a brush back having a 125 facial recess, a brush head removably seated in said recess flush with the said back and comprising sections having coöperating side members forming a marginal brush head rim, spaced interfitting members carried by 130

the side members, bristle tufts on said side and interfitting members, and means engaging one of said brush head sections for locking the combined sections in said recess.

5 4. In combination, a brush back having a facial recess, a brush head removably seated in said recess flush with the said back and comprising sections having coöperating side members forming a marginal brush head
10 rim, spaced interfitting members carried by the side members, bristle tufts on said side

and interfitting members, and locking means for securing the brush head in said recess and comprising means on one of said sections for engagement with the brush back 15 and coöperating means on the brush head for engagement with latching means on the brush back at a point remote from the other engaging means.

In testimony whereof I affix my signature. 20

KATHERINE T. BARAL. [L.s.]
